John Reichert INVENTOR.

BY
Christie & Beck ATTORNEY.

UNITED STATES PATENT OFFICE.

JOHN REICHERT, OF RACINE, WISCONSIN.

DESIGN FOR A TRACE-CARRIER.

59,682.

Specification for Design.

Patented Nov. 15, 1921.

Application filed November 27, 1920. Serial No. 426,817. Term of patent 14 years.

To all whom it may concern:

Be it known that I, JOHN REICHERT, a citizen of the United States of America, residing at Racine, in the county of Racine and State of Wisconsin, have invented a new, original, and ornamental Design for a Trace-Carrier, of which the following is a specification, reference being had to the accompanying drawing, forming part thereof.

Referring to the accompanying drawings: Figure 1 is a perspective view of a trace carrier embodying my new design.

Fig. 2 is a top plan view thereof.

I claim:

The ornamental design for a trace carrier, substantially as shown.

JOHN REICHERT.
